UNITED STATES PATENT OFFICE.

THOMAS A. NEVINS, OF NEW YORK, N. Y., ASSIGNOR, BY MESNE ASSIGNMENTS, TO
HERCULES MATCH CORPORATION, OF NEW YORK, N. Y., A CORPORATION OF NEW
YORK.

MATCH-MAKING MACHINE.

Application filed November 28, 1922. Serial No. 603,865.

To all whom it may concern:

Be it known that I, THOMAS A. NEVINS, a citizen of the United States, and a resident of New York city, in the county of New York and State of New York, have invented a new and Improved Match-Making Machine, of which the following is a full, clear, and exact description.

The present invention relates to new and useful improvements in match-making machines, and it pertains more particularly to that type of machine employed for manufacturing match packets or matches in book form.

15 It is one of the objects of the invention to provide a new and improved form of mechanism for forming the strips which form the back of the match packets.

It is another object of the invention to 20 provide a new and improved folding mechanism whereby the books are bent or folded to form a closed packet containing matches.

Suction or vacuum has been heretofore employed in the feeding of the strips, but in 25 such mechanism it is the common practice to employ a mechanically driven or controlled valve whereby the vacuum is intermittently broken to release the strip from the vacuum feeding mechanism. The

30 vacuum mechanism described has disadvantages, among the greatest of which is that when the vacuum is broken a sudden release of the strip causes the same to become disarranged with respect to its holder or carrier and thus ruins the operation of the machine.

It is a further object of the present invention to provide a suction or vacuum feeding mechanism wherein the vacuum is 40 maintained constant, and the movement of the carrier or holder of the strips forming the match book serves to move the match book out of contact with the nozzle of the suction device, thus eliminating the necessity of a mechanically timed valve for establishing and breaking the vacuum or suction of the feed.

With the above and other objects in view, reference is had to the accompanying drawings, in which—

Figure 1 is a top plan view of a machine constructed in accordance with the present invention;

Fig. 2 is a view in front elevation thereof;

Fig. 3 is a detail sectional view showing 55 the operation of the suction or vacuum feed;

Fig. 4 is a detail top plan view of the vacuum feeding device;

Fig. 5 is a detail sectional view showing 60 the folding in one station;

Fig. 6 is a similar view showing the final folding mechanism and its operation;

Fig. 7 is a detail view partly in section, showing the manner of the operation of this folding mechanism.

Figure 8 is a detail vertical sectional view 65 of the mechanism employed for feeding the matches to the match cover blanks.

Referring more particularly to the drawings, the reference character 15 designates 70 the machine bed, and said bed is supported by means of legs or the like (not shown).

Mounted on the bed 15 are two bearings 16, and revolubly mounted in said bearings 16 is a shaft 17, which extends longitudinally 75

of the bed. The reference character 18 designates a power pulley, and said pulley is carried by a shaft 19, to which is se- 80

cured in such manner as to rotate therewith, a clutch collar 20. This clutch collar 20 is 85

adapted to engage a clutch collar 21 carried by a gear immediately below a gear 22, which latter gear is mounted upon the shaft 17. The reference character 23 designates a 85

lever pivoted as at 24, for operating the clutch collar 20. By this mechanism it is apparent that when the clutch collar 20 is engaged with the clutch element 21, the gear (not shown) will be operatively connected to the shaft 19, and will serve to drive 90

the gear 22, and through the medium there- 95

of, impart rotary motion to the shaft 17.

Mounted in bearings 25, is a shaft 26, which extends at right angles to the shaft 17, and said shaft 26 carries a bevel gear 27 95

adapted to mesh with a bevel gear 28 opera- 100

tively connected to the shaft 17 in such a manner that said bevel gear 28 will, through the medium of the bevel gear 27, drive the shaft 26. Mounted in bearings 29,

is a shaft 30, and said shaft 30 has opera- 105

tively connected thereto a bevel gear 31, which in turn meshes with a bevel gear 32 carried by the shaft 17 in such a manner

that through the medium of the bevel gear 31, the bevel gear 32 will drive the shaft 30.

As more clearly shown in Fig. 2, bearing

members 33 are secured to the under face of

- the machine bed 15, and mounted in said bearing members 33, is a shaft 34. This shaft 34 has, adjacent the power end of the machine, a gear 35, and at the other end 5 said shaft is provided with a bevel gear 36, which in turn meshes with a bevel gear 37 carried by a shaft 38, and upon the opposite end of the shaft 38, a crank 39 is carried. This crank 39 has a crank pin 40, and said 10 crank pin 40 serves to drive a Geneva movement 41, more clearly shown in Fig. 2. Adjustably secured to the Geneva movement by means of bolts or the like, 42, is a sprocket wheel 43, said bolts 42 passing through 15 arcuate slots 44 to provide for the adjustability of the sprocket wheel.
- Mounted upon the sprocket wheel 43 is a sprocket 45, and at the opposite end of the machine a sprocket 46 is rotatively mounted, 20 as at 47. Passing around the sprockets 43, 45 and 46, is an endless conveyer 48, and said endless conveyer serves to carry the elements forming the completed article, through the machine to the several positions 25 in which the separate operations are carried out. As best seen in Fig. 2, this conveyer 48 comprises a plurality of carriers 49, which are connected by means of pivotal links 50. Each of these carriers 49 has a depressed portion 51 in which the various elements are packed to be retained.
- Carried by a standard 52 secured to the main bed 15 is a hopper 53, and said hopper is adapted to carry elongated strips of cardboard or similar material from which the books containing matches are formed. This hopper is provided with a spring 54, by means of which the cardboard strips are prevented from accidental displacement from 30 the lower end of the hopper. This spring, however, permits of the withdrawal of the cardboard strips from the bottom of the hopper by the vacuum or suction device.
- The bearings 25 heretofore mentioned are 35 carried by standards 55, and, as more clearly shown in Fig. 3, the shaft 26 projects beyond the innermost bearing 25. This shaft is formed with a crank arm 56, and said crank arm is adjustable circumferentially of 40 the shaft 26 by means of a screw 57, said crank arm being split as at 58. Connected to the crank arm 56, as at 59, is a lever 60, and the opposite end of said lever is provided with an elongated slot 61.
- Pivotal secured as at 62 to the standard 52 heretofore described as carrying the hopper 53, is a right-angular member 63. This right-angular member 63 has its upper end provided with a pin 64 adapted to operate in 55 the elongated slot 61 of the lever 60. The opposite end of this right-angular member is provided with two arms 65, more clearly shown in Fig. 4, and each of these arms is provided with a nozzle portion 67. Leading 60 from the nozzle portion 67 to a suitable vac-
- uum producing device (not shown) is a tube 68, by means of which vacuum is created at the nozzle 67. In order to form a more perfect grip on the cardboard, the nozzle 67 is provided with a friction producing insert 68 70 in the form of a rubber gasket or the like. Connected to the bearing 25, as at 70, is a spring 69, and the opposite end of the spring is connected to the pin 64 heretofore mentioned. The mechanism just described is located preferably at the right of the machine 75 and overlies the conveyer 48 heretofore mentioned.
- Carried by the front of the machine is a feed guide 71, and said feed guide 71 is 80 adapted to receive the match strips 72, it being understood that two of these match strips are fed together to the machine, and the match strips are moved by a step-by-step mechanism to be hereinafter more fully described. These match strips are fed towards 85 a cutting mechanism of conventional form, and after they are cut they are fed into the machine by a feeding mechanism common to this type of machine and designated by the 90 reference character A in Fig. 2.
- Carried by the shaft 17 is an eccentric 74, and operated by the eccentric 74 is a rod 75. As more clearly shown in Fig. 5, the rod 75 operates a lever 76, pivotally mounted as at 95 77, and to which lever 76 the rod 75 is pivotally mounted as at 78. This lever has an angularly disposed extension 79, and rigidly secured thereto is a substantially right-angular finger 80, which is adapted to swing 100 in a vertical plane as indicated by the full and dotted lines in Fig. 5. This finger 80 is adapted to swing upwardly and bend the material from which the book is formed, from the dotted-line position to the full-line 105 position shown in Fig. 5, upon each operation of the eccentric 74. It is to be understood that this mechanism is mounted behind the conveyer 48, as clearly shown in Fig. 5, and that overlying this mechanism 110 there is a guard 81, which serves to hold the matches in engagement with the material from which the book is formed. To the left of this mechanism, there is a second folding mechanism, and said second folding mechanism 115 is adapted to fold over that section of the material forming the book which constitutes the cover or flap in the finished product.
- As more clearly shown in Figs. 6 and 7, a 120 cam 82 is secured to the shaft 17, and pivotally mounted, as at 83, is a rocking arm 84, one end of which has a roller 85 engaging the cam 82, whereby the arm 84 will be rocked about its pivotal point 83 upon each rotation of the shaft 17. To maintain the roller 85 in engagement with the cam 82, a spring 86 is employed. This lever 86 has an upwardly and forwardly disposed curved portion 87, which is pivotally connected as 125 130

at 88 to a rod or link 89. The forward end of this rod or link is pivotally connected as at 90, to a link 91, which in turn is pivoted at its upper end as at 92. This link is 5 adapted to operate a block 93, and secured to the block 93 by means of a screw 94, is an arm 95, the outer end of which is curved as at 96. As the block is rotated, the plate 95 is adapted to swing from the horizontal 10 position in which it is shown in full lines in Fig. 7 to the vertical position in which it is shown in full lines in Fig. 6, and in so doing is adapted to engage that portion of the book forming the flap and fold the same 15 over as shown in Fig. 6.

Just beyond this mechanism, is a third folding mechanism, and this third folding mechanism comprises a reciprocating member 97 mounted in guides or bearings 98. 20 The rear end of this reciprocating member 97 is bifurcated, as at 99, and provided with a roller 100, which in turn is adapted to engage a cam 101 carried by the shaft 17 in such a manner that each time the shaft 17 25 is rotated, the reciprocating member will be moved forwardly and will serve to bend the upwardly standing flap heretofore mentioned and shown in dotted lines in Fig. 6, downwardly to the full-line position shown 30 in Fig. 6 where it overlies the flap or cover as shown.

In order to cause a reciprocation of the member 97 rearwardly of the machine, a spring 102 is employed. After this has been 35 done, the books are next moved to the stapling mechanism shown as of conventional form and designated by the reference character 103 in Fig. 1.

The feeding mechanisms heretofore referred to is operated by means of the shaft 30, the forward end of which is provided with a crank 104, to which is pivotally connected a lever 105. This lever 105 has pivotal connection at one end with a rocking 40 member 106, the end of which is provided with a right-angular extension 107. Pivotally connected, as at 108, is a lever 109, similar in construction to the lever 106, and said levers are pivotally connected by means 45 of a rod 107'. By this construction it is apparent that each time the crank member 104 is operated, the levers 106 and 109 will be elevated and again depressed. Simultaneously with this movement a projection 50 110 on the rod 107' engages between stops 111 and causes a reciprocating movement of a member 112 on which the levers 106 and 109 are pivotally mounted as indicated at 113 and 114, respectively.

60 The device operates in the following manner:

The hopper 53 is filled with the blanks from which the covers or books are formed and the matches are placed in the feed guide 65 71, preferably in the form of two superim-

posed strips. The machine is now started and immediately the feeding mechanism moves the match strips forward or to the right in Fig. 1. Simultaneously with this operation, the suction device has been elevated as shown in dotted lines in Fig. 3, and has caused the bottom blank to be removed from the hopper 53. As this suction device moves downwardly, the bottom strip is deposited in the carrier 49 of the conveyer 48, 70 which is directly beneath the hopper 53, it being understood that the conveyer is moved in a step-by-step manner by the Geneva movement 41 heretofore mentioned. As the machine continues to operate, the blanks 75 are removed singly from the hopper 53 and deposited in the empty carriers of the conveyer as they are positioned therebeneath. With the parts in the position shown in Fig. 3, a movement of the conveyer to the left of said figure will move the blank out of contact with the nozzle of the vacuum or suction feeding device and will position an empty carrier of the conveyer in a position to receive one of the blanks upon the 80 next operation of the suction device. As shown in Fig. 1, these blanks move to the left of the machine, the blanks being designated by the reference character B, and when they reach the position designated by 85 the reference character B' in Fig. 1, the matches designated by the reference character C, which have been severed from the strip are moved by the feeding mechanism on to the blank B as designated by the reference character B² in Fig. 1. After this has been done, the bending mechanism in the form of a curved arm 80 is brought into play and the short end, designated by the reference character C², is bent upwardly as 90 shown in full lines in Fig. 5. To maintain this upwardly bent portion C² in its vertical position, a small stationary guide is employed. The conveyer now moves the blank with the matches thereon to the position designated by the reference character B³ in Fig. 1, and at this position the folding mechanism heretofore described and shown in Fig. 6 and 7 is brought into play 95 to close the match book, after which it is moved one step farther to the stapling device, and after the staple has been attached, the match book complete and designated by the reference character 120, is moved through the machine.

Co-operating with the conveyer 48, is a plate 121, which serves to maintain the completed match books in the conveyer until they reach the point designated by the reference character X, at which point they are discharged into a suitable receptacle (not shown).

From the foregoing it is apparent that the present invention provides a new and improved machine especially adapted for 125 130

- forming match packets or boxes in which the operation is greatly reduced and the travel of the device from one station to the other during the operation is greatly reduced, substantially right-angular member engaging 60 the short flap of the match book during its movement and moving the same to vertical position.
- 5 thus increasing the speed and efficiency of operation of the machine. Furthermore, by the construction of the vacuum or suction feeding apparatus, it is apparent that it is not necessary to have a timed valve which 10 will automatically release said vacuum but that sufficient vacuum by this construction can be obtained to position the blanks in the conveyer, and, at the same time, said vacuum is not strong enough to prevent movement 15 of the blanks relative to the vacuum nozzle through the medium of the conveyer.
- Heretofore so far as is known, the operation shown in Fig. 5 of first folding up the section C² of the book blank, and subsequently 20 folding the flap inwardly of the book, and last, folding the section C² thereover just prior to the stapling operation, has not heretofore been employed. I am aware that this operation has been carried out by 25 means of stationary folding guides but movable folding means to perform this operation has not been disclosed in the art.
- What is claimed is:
1. In a match-making machine of the type for making book matches, a folding mechanism for closing the book before the stapling operation takes place, said means comprising a rocking shaft and a hooked member carried thereon and adapted to fold the 30 larger flap of the match book over into position above the matches in the book, and a reciprocating member for folding the smaller flap to position overlying said larger flap.
  2. In a match-making machine of the type for making book matches, mechanism for folding the match books, said mechanism comprising vertically movable means for folding the short flap of the finished book 35 to a vertical position, means for folding the long flap of the book in position over the matches, and means for subsequently folding the short flap over the long flap to close and maintain closed the match book.
  3. In a machine for making matches of the book type, means for folding the short flap of the book to vertical position, said means comprising a rocking shaft, means for operating said rocking shaft, an angular projection carried by the rocking shaft and operating therewith, and a substantially 40 right-angular member carried by said angular projection and movable in a vertical plane by the action of said shaft, said sub-
  4. In a machine for making matches of the book type, means for folding the longer flap of the match book to position over the matches, said means comprising a curved member adapted for swinging vertical movement and adapted in its movement to engage the longer flap of the book and move 45 the same into position over the matches contained therein, and means for operating said curved member, said means comprising a reciprocating rod, a curved member pivotally carried by the bed of the machine and pivotally connected at one end to said rod and a driven cam for operating said curved member. 50
  5. In a match-making machine, a conveyer, a hopper for containing pasteboard blanks, means for depositing the pasteboard blanks upon the conveyer, means for depositing matches upon the pasteboard blanks, vertically movable means for folding one of the ends of the pasteboard blanks to a vertical position, transversely movable means for folding the opposite end of the pasteboard blanks into position overlying the matches carried by the pasteboard blanks, reciprocating means for folding the vertically disposed end of the blank over the folded end of the blank to close the book, and means for stapling said last folded end of the blank to the body of the blank to maintain the folded flap in closed position, and means for subsequently discharging said completed match book from the machine. 55
  6. In a match-making machine, an intermittently movable conveyer, a hopper for carrying match-book blanks, a continuously operating suction nozzle for removing the match-book blanks from the hopper and depositing them upon the conveyer, means for depositing matches upon said match-book blanks, means for folding one end of said match-book blanks to a vertical position, transversely movable means for folding the opposite end of the match-book blanks to horizontal position over the matches carried by the blanks, transversely reciprocating means for subsequently folding the first-mentioned folded end over the second-mentioned folded end, and means for stapling the last-mentioned folded end to the body of the blank to retain the last-mentioned folded end in closed position. 60

THOMAS A. NEVINS.
